Specification for Design.

Patented July 15, 1919.

Application filed April 9, 1919. Serial No. 288,888. Term of patent 3½ years.

To all whom it may concern:

Be it known that I, FREDERICK E. GREENE, a citizen of the United States, residing at Mount Vernon, Westchester county, State of New York, have invented a new, original, and ornamental Design for a Vase for an Automobile or a Similar Article of Manufacture, of which the following is a specification, reference being had to the accompanying drawing, forming a part thereof.

In said drawing:

Figure 1 is a side view of a vase embodying my ornamental design.

Fig. 2 is a view looking up at the same from the bottom.

I claim—

The ornamental design for a vase for an automobile or a similar article of manufacture, substantially as shown.

FREDERICK E. GREENE.
